PUMP

Arnold S. Soberg, Elmhurst, Ill., assignor to
Sochris Development Company, Chicago, Ill., a
corporation of Illinois

Application June 23, 1949, Serial No. 100,900

9 Claims. (Cl. 103—46)

1

This invention is directed to new and useful improvements in pump of the type wherein a cylinder and piston is positioned adjacent a source of water or liquid in the ground within a well casing filled with liquid and pressure is exerted on the liquid within the casing to depress the piston and means are provided to return the piston to move liquid from the source upwardly.

The primary object of this invention is to provide such a pump of simple construction wherein an air column is compressed on the downstroke of the piston to provide the means for returning the piston to starting position when pressure against the water column is released.

Another object is to provide means for replacing air in the column should it become depleted.

Still a further object is to provide such pump assembly that is relatively inexpensive to manufacture, lighter in weight, and easy to maintain due to its simplicity of design and freedom from mechanical means for returning the piston to upper positions.

Other objects and advantages will become apparent from the following detailed specifications:

In the drawings:

Fig. 1 is a sectional view of a pump assembly embodying this invention with the piston in normal position.

Fig. 2 is a view similar to Fig. 1 but showing the piston in its depressed position.

Figs. 3 and 4 similarly illustrate another form of pump assembly embodying this invention.

In detail, the well casing 1 is sunk in the ground to a source of liquid to be pumped. A cylinder 2 is suspended within the casing 1 adjacent the source of the liquid by any suitable means, for example by means of an expanded ring assembly 3, as described in my copending application Serial Number 767,673, filed August 9, 1947. Cylinder 2 houses the pumping mechanism which includes cylinder 4, which is a tube closed at its top 5 but with bottom end open. Mounted on the top 5 is a rod 6 to which is secured a piston head 7 having irreversible outlet ports 8 with closures 9 of the usual well known construction. Piston head 7 is provided with suitable sealing means 10 adapted to permit sliding movement within cylinder 2 but to prevent leakage of liquid through head 7 when ports 8 are closed. Piston head 7 and cylinder 4 form a piston reciprocally mounted within cylinder 2.

Rigidly mounted on the lower end of cylinder 2 is an arched cap assembly 11 including an irreversible inlet port 12 with closure 13 of usual well known construction, permitting liquid to enter cylinder 2 through port 12 and around the

2

arched portion of 11. Extending upwardly from assembly 11 is a hollow tube 14 to the top of which is secured a sealing cup 15 extending across cylinder 2 but permitting sliding relationship therewith without liquid or gas leakage. Thus cup 15 and tube 14 form a rigid piston within cylinder 4 which is slidably movable with relation thereto. Tube 14 extends through cup 15.

This pump assembly thus provides a liquid chamber 16 open at the bottom by inlet port 12 and at the top by outlet ports 8. There is also provided an air chamber 17 to which tube 14 connects providing an air conduit 18. A tube 19 connects with conduit 18 through assembly 11. This tube 19 leads to a source of air or gas 20 and a valve 21 controls the supply from the source 20. A gauge 22 indicates the air pressure in the chamber 17 so that when it falls below the determined minimum the valve 21 may be opened to replenish the supply.

Connected to the interior of casing 1 is a conduit 22 leading to a piston assembly 23 adapted to provide pulsating pressure to the liquid in the casing as is well known.

Leading from casing 1 is a conduit 24 connected to a liquid storage tank 25 through pressure valve means 26.

In operation the entire casing 1, piston assembly 23 and chamber 16 are filled with the liquid to be pumped, water. Piston 27 is moved from the position in Fig. 1 to that in Fig. 2 to exert pressure on the column of water in the casing 1. The pressure will depress the piston formed by piston head 7, valve assembly 8, 9 and cylinder 4 from Fig. 1 position to Fig. 2 position. During this downward movement outlet ports 8 are opened to permit movement through the water column. Chamber 16 is decreased in volume and liquid is necessarily displaced through and to above piston head 7. Simultaneously the volume of air chamber 17 is decreased to compress the air therein. As piston 27 returns to first position the pressure on the liquid column is released and the compressed air in chamber 17 forces cylinder 4 and its associated piston head 7 back to its Fig. 1 position. On its return, outlet ports 8 are closed to move the liquid above it upwardly. Also on the return movement valve assembly 11 opens to take in liquid to chamber 16. As liquid is displaced from chamber 16, as described, the upper end of the thus augmented liquid column moves into conduit 24 through pressure valve 26 to tank 25.

From time to time, as needed, air can be supplied to air chamber 17 by opening valve 21. It

is apparent that gas can be substituted for air without affecting the results.

This pump assembly dispenses with heavy spring construction for returning the piston 4 to upper position. Thus the assembly is of less weight, not subject to spring breakage and less expensive to make.

It is apparent that other means may be utilized to maintain the necessary air pressure in chamber 17 such as, for example, a small cylinder of CO₂ positioned in chamber 17 and provided with an automatic regulating valve that would function to admit CO₂ to chamber 12 when the pressure fell below a certain minimum. Likewise, an air bladder can be positioned in chamber 12 containing a supply of air and sealed against loss.

An alternate embodiment of the invention is shown in Figs. 3 and 4 wherein the well casing is indicated by reference character 31 and the seal, corresponding to the ring assembly 13 of Figs. 1 and 2, is indicated by reference character 32. Likewise a cylinder 33, corresponding to cylinder 16 of Figs. 1 and 2, is formed on its lower end with an irreversible inlet port 34 with closure 35 which, when open, permits water to enter cylinder 33 around the arched portion 36. Arched portion 36, unlike its counterpart 11 in Figs. 2 and 3, provides a support for inner cylinder 37.

Mounted within cylinder 33 is piston assembly 38 provided with irreversible outlet ports 39 with closures 40 and depending piston rod 41. At the lower end of piston 41 is piston assembly 42 slidably mounted in cylinder 37. A shield 43 may be provided, if desired, to prevent sand or other material from interfering with the operation of piston 42.

The operation of the modification shown in Figs. 3 and 4 is as follows:

On the downward stroke of the water column the piston and rod assembly 38, 41 and 42 moves from the normal position shown in Fig. 3 to the position shown in Fig. 4, thereby compressing the air in cylinder 37 below piston 42. During this downward movement valves 40 are opened, thus permitting movement of the piston through the water column. Chamber 33 is thereby decreased in volume and the liquid thus displaced passes upwardly through ports 39. Simultaneously the air in the lower portion of cylinder 37 is compressed.

When the downward stroke of the water column is completed and the downward pressure thereon is released, the compressed air in cylinder 37 forces the piston assembly back to the initial position, illustrated in Fig. 3. As this upward movement takes place the valves 40 are closed, thus lifting the water column, and the valve 35 open to draw a fresh increment of water into cylinder 33.

Air supply line 44, corresponding to the air tube 19 of Fig. 1, or similar expedients such as hereinabove described may be employed to maintain the desired air pressure in cylinder 37.

I claim:

1. A pump assembly comprising a cylinder having an open upper end, an irreversible inlet at its lower end, a rod extending upwardly from the lower end and terminating below the upper end, a sealing cup on the upper end of said rod, a movable piston assembly comprising a second cylinder with closed upper end slidably mounted around said cup and extending above said cup to provide an air chamber and below said cup, its lower end being open, a sealing cup mounted on the upper end of said second cylinder and in

sliding relation with the upper end of the first cylinder, irreversible outlets in said second sealing cup, means for maintaining a predetermined pressure of air in said air chamber, said assembly adapted for positioning within a well casing and its piston assembly for reciprocation to move liquid upwardly.

2. A pump assembly comprising an outer stationary cylinder, an irreversible inlet at the bottom thereof, an inner movable cylinder closed at its upper end, a piston head secured to the inner cylinder and in sliding sealed relation with the outer cylinder to provide a liquid chamber between the two cylinders, an irreversible outlet through said piston head, a piston within the second cylinder and affixed to the first cylinder providing a closed air chamber within the second cylinder adapted to be decreased in volume by the downward movement of the inner cylinder, said assembly being adapted for positioning within a well casing and its movable cylinder to be reciprocated by variations of pressure therein.

3. A pump assembly comprising an outer stationary cylinder, an irreversible inlet at the bottom thereof, an inner movable cylinder closed at its upper end, a piston head secured to the inner cylinder and in sliding sealed relation with the outer cylinder to provide a liquid chamber between the two cylinders, an irreversible outlet through said piston head, a piston within the second cylinder and affixed to the first cylinder providing a closed air chamber within the second cylinder adapted to be decreased in volume by the downward movement of the inner cylinder to provide a compressible air cushion for returning the movable cylinder to its uppermost position and means for maintaining the desired volume of air in said air chamber, said assembly being adapted for positioning within a well casing and its movable cylinder to be depressed by an increase of pressure within the casing.

4. In a pump assembly adapted to be positioned in a well casing for operation by changes in pressure therein, the improvement that comprises an outer cylinder, an irreversible inlet to said cylinder, a rigid piston secured to and within said cylinder, a movable smaller cylinder with closed upper end slidably mounted around said piston in sealed relation to form a closed air chamber within the second cylinder, a piston head secured to the inner cylinder and slidably mounted within the larger cylinder and an irreversible outlet through said piston head, whereby when the smaller cylinder and associated piston head is moved downwardly by pressure within the casing the outlet will be opened and the air chamber decreased in volume to compress air therein and when moved upwardly by the air compressed in said air chamber the said inlet will be opened.

5. In a pump assembly adapted to be positioned in a well casing for operation by changes in pressure therein, the improvement that comprises an outer cylinder, an irreversible inlet to said cylinder, a rigid piston secured to and within said cylinder, a movable smaller cylinder with closed upper end slidably mounted around said piston in sealed relation to form a closed air chamber within the second cylinder, a piston head secured to the inner cylinder and slidably mounted within the larger cylinder, an irreversible outlet through said piston head and means for maintaining the desired amount of air in said air chamber.

6. In a pump assembly adapted to be positioned in a well casing for operation by changes in pres-

sure therein, the improvement that comprises an outer cylinder, a closure at its lower end, an irreversible inlet through said closure, a piston of smaller diameter than said cylinder secured thereto and extending upwardly therein, a piston head movably mounted within said cylinder, an irreversible outlet therethrough and a second cylinder of smaller diameter than the first with closed upper end secured to said piston head and depending therefrom and receiving said piston in reciprocal relation to form a closed air chamber of variable size between the piston and the closed upper end of the tube to provide a compressible air cushion acting against the piston head.

7. In a pump assembly adapted to be positioned in a well casing for operation by changes in pressure therein, the improvement that comprises an outer cylinder, a closure at its lower end, an irreversible inlet through said closure, a piston of smaller diameter than said cylinder secured thereto and extending upwardly therein, a piston head movably mounted within said cylinder, an irreversible outlet therethrough and a second cylinder of smaller diameter than the first with closed upper end secured to said piston head and depending therefrom and receiving said piston in reciprocal relation to form a closed air chamber of variable size between the piston and the closed upper end of the tube to provide a compressible air cushion acting against the piston head, a tube leading through said piston to said chamber, and a source of air under pressure connected with said tube.

8. A pump assembly comprising an outer cylinder rigidly mounted within a well casing, said outer cylinder being open at its upper end and formed with an irreversible inlet valve at its lower end, a piston in water tight engagement with and slideable within said outer cylinder, an outlet port on said piston provided with a one-way valve to permit passage of liquid toward the upper end

of the cylinder, an inner cylinder mounted within the outer cylinder, said inner cylinder being of substantially less diameter than the outer cylinder and closed at one end, a piston in water tight engagement with and slideable within said inner cylinder, said piston forming a gas chamber between it and the closed end of the cylinder, and means for maintaining predetermined pressure in said gas chamber, a movable connection between said gas chamber and the piston in the outer chamber whereby a predominant pressure in the gas chamber will move said piston toward the upper end of the outer cylinder.

9. A pump assembly comprising an outer stationary cylinder, an irreversible inlet at the bottom thereof, an inner cylinder closed at its lower end and rigidly secured at said end to the lower portion of the outer cylinder, a piston head secured to the outer cylinder and a piston head secured to the inner cylinder each piston head being in sliding sealed relation with its respective cylinder, a rigid connection between said two piston heads, and an irreversible port in the piston head on the outer cylinder for passage of liquid upward therethrough, the inner cylinder providing an airtight chamber below its piston head adapted to be decreased in volume by the downward movement of said piston to provide a compressed air cushion for returning the piston to its uppermost position when downward pressure against piston head is released.
